UNITED STATES PATENT OFFICE.

EDDY T. THOMAS, OF NEW YORK, N. Y.

ROTARY ENGINE.

No. 861,918.

Specification of Letters Patent.

Patented July 30, 1907.

Application filed April 18, 1906. Serial No. 312,346.

To all whom it may concern:

Be it known that I, EDDY T. THOMAS, a citizen of the United States, residing at New York city, in the county of New York and State of New York, have invented certain new and useful Improvement in Steam Rotary Engines, of which the following is a specification.

The object of this invention is to produce a rotary steam engine with a circumferential steam chest formed between the inner wall of the cylinder and the periphery of the piston, that the steam may be confined to the periphery of the said piston, thereby gaining by leverage a large percent of power with the same units of heat over engines classed as "reciprocating", a further object is to automatically open and close the ports that the steam at each revolution may be shut off and allowed to expand the same as in the "Corliss" engines, thereby economizing in fuel in addition to the leverage.

A further object is to admit the steam between a fixed head and a rotary piston in the same manner or principle as steam is admitted between the heads and piston of a reciprocating engine and at the same time to avoid the reversing motion.

A still further object is to provide means to regulate the port valves so they can be readily set to remain open a longer or shorter time.

The invention consists in a stationary cylinder forming the outer wall of a steam chest, and a rotary piston the periphery of which forms the inner wall, the said piston being provided with a pivoted lug extending to the inner wall of the cylinder, a fixed lug secured to the inner wall of the said cylinder extending to the periphery of the piston, an automatic opening and closing port valve to admit steam between the pivoted and fixed lugs, a cam or inclined plane to swing the pivoted lug and exhaust recesses leading from said steam chest, a piston packing ring spring yielding packing for the lugs and a recess for the pivoted lug in the periphery of the piston.

Figure 1 represents a side view of the engine showing valves, cams and pipe. Fig. 2 is an edge view of Fig. 1. Fig. 3 represents Fig. 1 having one of the heads removed showing the interior working parts. Fig. 4 shows the spring and cross section of the ring packing of the piston. Fig. 5 is a side view of the fixed lug and cam of the cylinder. Fig. 6 is a cross sectional view of Fig. 5. Fig. 7 is a side view of the pivoted lug. Fig. 8 is a cross sectional view of the port valves and seats. Fig. 9 shows the pivoted lug to form a part of the cylinder and the fixed lug located on the piston. Fig. 10 shows the fixed lug and cam as forming a part of the piston while the adjustable lug or gate slides in the cylinder casing. Fig. 11 represents a pivoted lug having steam port located central to equalize the steam pressure and Fig. 12 shows a spring and cam operated shaft to take the place of the adjustable lug.

A in the several figures represents a cylinder cast integral with the base A¹, this cylinder supports the side flanges A² which form bearings A⁵ for the arbor A³. A⁴ Figs. 1 2 and 3 is a piston secured to the arbor A³ which being of less diameter than the inner circumference of the cylinder A forms a space A⁶ which constitutes the steam chest, and in which are located the several parts that form the lugs also the ports for the steam.

E Figs. 3 and 4 is a metal packing ring which by aid of the springs E¹ reduce the friction of the piston against the flanges A² and prevent steam from escaping from the arbor bearings A⁵, only one of these rings are shown but more may be employed in large engines.

A⁷ in Figs. 3 and 7 is a piston lug pivoted at its base and held open by a coiled spring A¹² these lugs in action take the place of the piston in reciprocating engines and are forced around by the action of the steam, rotating the arbor A³, that no steam may escape past the free end or the edge contacting with the periphery of the steam chest A⁶ of these lugs, a thin metal spring A¹¹ as shown in Figs. 3 and 7 is inserted to the face of the flanges, their free ends resting against the cylinder, which with the back and down pressure of the lug A⁷ whenever the steam is admitted forms a secure packing and also compensates for any wear as the lugs are wider than the chest A⁶.

A¹⁰ Figs. 3 5 and 6 is a stationary lug secured to the cylinder A or an integral part thereof it extends from side to side of the steam chest A⁶ and its free edge contacts with the periphery of the piston A⁴ (forming and answering the purpose of the cylinder head of a reciprocating engine) confining the steam at one point, while the piston lug A⁷ is forced around by steam and expansion thereof.

At each end of the lug A¹⁰ and forming an integral part are cams A⁹ against which the back of the pivoted lugs A⁷ contacts causing them to swing or close into the recesses of the piston shown by dotted lines Fig. 3 as they pass the lugs A¹⁰ and to permit them to open gradually to the position shown, the two having concaved surfaces A⁹ merging into a convexed surface forming a curved line of inner and outer circles which prevent lug A⁷ from leaving the periphery of the steam chest A⁶ thereby preventing any blow or noise in closing or opening.

C Figs. 1 2 and 8 are port valve lugs formed integral with the side A² through which a tapering valve seat is formed as shown in Fig. 1 and C⁹ Fig. 8. C¹ Figs. 1 2 3 and 8 is a tapering valve having a recess from the inner end up to a little beyond the dotted line . . . x Fig. 2 which intercepts the port hole C¹⁰.

C² Figs. 1 and 2 is a crank arm secured to the outer end of the valve stem C¹, it is provided with a stud C³ and a roll C⁴ which contacts with the periphery of the cams B and B¹ causing the valve C¹ to turn, so the port C¹⁰ Fig. 8 may be closed as shown or swung to the end

of the feed pipe C⁵; by the aid of this construction the ports are opened when the lug A⁷ is in the position shown in Fig. 3 and closed when the lug A⁷ reaches the dotted line . . . x³ shutting off the steam which expands until the lug A⁷ is opposite the dotted lines . . . x¹ at this point the exhaust begins.

B and B¹ are cams secured to the arbor A³, these cams are cut in duplicate each provided with two gradual elevations B⁴ diametrically opposite, and two sharp inclines, B⁶ also opposite each other, but before placing them upon the arbor A³, they are reversed as shown in Fig. 1 and secured by the bolt B³, this position of the bolt in the center of the slot B² brings the two gradual elevations B⁴ on each of the cams, this junction at B⁶ form a double elevation for the roll C⁴ to pass over, which keeps the ports open the full or longest time, by aid of the opposite adjustment the ports are closed quicker giving the steam more time to expand. The rolls C⁴ are held against the cams B and B¹ by any suitable spring (not shown).

The pipes C⁵, C⁶ C⁷ and C⁸ are feed pipes to carry the steam into the ports as shown in Figs. 1 and 2.

D D¹ and D² are exhaust pipes located as shown in Figs. 1 2 and 3.

25 In Figs. 9 10 11 and 12 the piston A⁴ is provided with a fixed lug A⁷ which in Figs. 9 10 and 11 are provided with a cam section A⁹ which gradually moves the pivoted and sliding heads F to permit the fixed piston head A⁷ to pass.

30 In Fig. 9 the revolving head F pivoted at F¹ has four sections or teeth which represent gear teeth, at each revolution of the piston this revolving head F. is turned one quarter around by the advancing lug A⁷ and is locked in place by the spring bolt F⁴.

35 F. in Fig. 10 is a sliding head and is automatically closed by the spring at its upper end and opened to permit the piston lug A⁷ to pass by the cam A⁹.

F Fig. 11 operates in the same manner as F in Fig. 9, only a spring F² keeps it in a vertical position.

40 A¹³ in Figs. 9 10 and 11 is an extra cap secured to the cylinder A.

G in Fig. 12 shows how the sliding head G² can be worked from the side by aid of the cam G and the projecting rim G¹ which push the head in while the spring 45 G³ open it.

A¹⁵ in Figs. 5 and 6 show a spring metal packing to prevent steam from going back of the head A¹⁰ the spring A¹⁶ is coiled and very light so as to avoid extra friction, the same form of packing for the piston 50 head A⁷ and is shown at A¹⁴ Fig. 11.

In Fig. 3 the piston A⁴ is provided with two lugs A⁷ and the cylinder A has two cams A⁹ and heads A¹⁰, there may be more or less and the cams A⁹ reversed or located on the piston A⁴ as shown in Fig. 10.

Having thus fully described my invention what I claim as new and desire to secure by Letters Patent of the United States is:

1. In combination, the cylinder A, the flanges A² the rotary piston A⁴ having lug A⁷ and the lug A¹⁰ having two concaved surfaces A⁹ merging into a convexed surface 60 forming a continuous inner and outer circle, which permits the lug A⁷ to be closed and opened without any noise or jumping from one point to another all forming the walls of a circular steam chest A⁶ around the periphery of the piston A⁴ in which steam is alternately admitted, shut off, 65 expanded and exhausted as set forth.

2. In combination, the cylinder A, the flanges A² having arbor bearings A⁵, the rotary piston A⁴ mounted on the arbor A³ or an integral part thereof, the packing ring E located in the end of the piston A⁴, the metal packing ring 70 spring E' to press the said ring against the flange A² a peripherical steam chest A⁶ having stationary and rotary walls, a stationary cylinder head A¹⁰ the concaved surfaces A⁹ merging into a convexed surface and the periphery of the chest A⁶ and a revolving piston head A⁷ between 75 which the steam is admitted, shut off and expanded as set forth.

3. In combination, the cylinder A, the flanges A² the rotary piston A⁴, the piston head A⁷ the metal spring packing plate A¹¹ secured to the head, the cylinder head A¹⁰ and 80 cam A⁹ as set forth.

4. In combination, the cylinder A, heads A², rotary piston A⁴, the heads A⁷ and A¹⁰ operating in the path of the circular steam chest A⁶, cam A⁹ having concaved surfaces merging into a convexed circle, forming an unbroken 85 curve line to operate the piston A⁷ the port C' and exhaust D² as set forth.

5. In combination, the cylinder A, heads A², rotary piston A⁴, the heads A⁷ and A¹⁰ the cam A⁹ having concaved and convexed curves forming a series of curves with the 90 periphery of the steam chest A⁶, which permits the head A⁷ to bear constantly against the said periphery, concaved and convexed curves, operating in the steam chest A⁶ the port C', valve C⁹ and exhaust D² as set forth.

6. In combination, the cylinder A, heads A², rotary piston A⁴ heads A⁷ and A¹⁰, the cam A⁹, port C', valve C⁹, 95 crank arm C² provided with stud C³ and roll C⁴ and cams B, B as set forth.

7. In combination, the cylinder A, heads A², rotary piston A⁴, heads A⁷ and A¹⁰, the cam A⁹, port C', valve C⁹, 100 crank arm C² provided with stud C³ and roll C⁴ and adjustable cams B, B having elevations B⁴ and depressions B⁵ to control the time of keeping the port C' open and shutting off the steam from the chest A⁶ as set forth.

8. In combination, the cylinder A, heads A², rotary piston A⁴, heads A⁷ and A¹⁰, cam A⁹ port C', valve C⁹ having steam passage C¹⁰, crank arm C², stud C³, roll C⁴, adjustable cams B, B having screw B³ and slot B² elevations B⁴ and depressions B⁵ as set forth.

9. In combination, the cylinder A, heads A², rotary piston A⁴, ring packing E, heads A⁷ and A¹⁰, cam A⁹ to close a sliding head in the steam chest C², port C', crank arm C² provided with stud and roll, cams B, B and exhaust D² as set forth.

In testimony whereof I have signed my name to this 115 specification in the presence of two subscribing witnesses.
